PORTABLE WATER SOFTENER

Robert J. Eckstrom, 8709 Able St. NE,
Minneapolis, Minn. 55433

Filed Sept. 11, 1967, Ser. No. 8,552

Term of patent 7 years

Int. Cl. D23—01

U.S. Cl. D23—3

FIGURE 1 is a perspective view of the portable water softener;

FIGURES 2 and 3 are top and bottom views respectively of the structure shown in FIGURE 1; and

FIGURES 4 and 5 are front and rear elevational views respectively of the structure shown in FIGURE 1.

I claim:

The ornamental design for a portable water softener, as shown.
